Patented Oct. 24, 1916.

2 SHEETS—SHEET 2.

UNITED STATES PATENT OFFICE.

JOHN M. B. LEWIS, OF LYNCHBURG, VIRGINIA.

DRINKING APPARATUS.

1,202,396.

Specification of Letters Patent.

Patented Oct. 24, 1916.

Application filed June 16, 1914. Serial No. 845,458.

To all whom it may concern:

Be it known that I, JOHN M. B. LEWIS, a citizen of the United States, residing at Lynchburg, in the county of Campbell and State of Virginia, have invented certain new and useful Improvements in Drinking Apparatus, of which the following is a specification.

This invention relates to improvements in drinking apparatus for cattle, such as cows, horses or the like, and has for its object the provision of apparatus of the above mentioned character which is highly sanitary, simple in construction, and inexpensive to manufacture.

Other objects and advantages of this invention will be apparent during the course of the following description.

The subject matter of this application is an improvement on the structure shown but not claimed in my pending application for cattle drinking apparatus filed February 10, 1914, Serial No. 817,727.

In the accompanying drawings forming a part of this specification and in which like numerals are employed to designate like parts throughout the same, Figure 1 is a fragmentary plan view of apparatus embodying the invention, Fig. 2 is a transverse sectional view taken on line 2—2 of Fig. 3, and Fig. 3 is a side elevation of the apparatus, parts being shown in longitudinal section and parts broken away, for the sake of illustration.

In the drawings, wherein for the purpose of illustration, is shown a preferred embodiment of the invention, the numeral 5 designates drinking receptacles, which are preferably identical and are separated at their inner ends by a transverse vertical partition 6, as shown. This partition 6 extends upwardly beyond the drinking receptacles 5 for a substantial distance, as shown.

Arranged below the drinking receptacles 5 in proximity to the partition 6, is a common approximately T-shaped outlet pipe or conduit 7, receiving the discharge of the water from both of the drinking receptacles 5, through outlet openings 8 as shown. The partition 6 is provided near one end thereof with a vertical opening, for receiving an overflow pipe 9, having its opposite ends open and its lower end discharging into the outlet conduit 7. It is obvious that the pipe 9 will prevent the level of the water within

the drinking receptacle 5 from rising above a predetermined height.

The numeral 10 designates a supply pipe, (see Figs. 1 and 2) having connection with a T-coupling 11, embodying downwardly extending curved pipe-arms 12, as shown. As more clearly shown in Fig. 2, the T-coupling 11 fits within an opening 13 formed in the upper portion of the transverse partition 6, and the pipe-arms 12 thereof are arranged upon opposite sides of this partition.

As more clearly shown in Fig. 3, each pipe-arm 12 is provided near its lower end with internal screw threads 14, for engagement with the upper screw-threaded end of a sleeve 15, included in a valve structure. This sleeve is provided at its upper end with a conical valve seat 16, decreasing in diameter downwardly, as shown. The sleeve 15 is arranged to discharge the water into the drinking receptacle 5, as shown. Arranged above the valve seat 16 is a vertically movable inlet valve 17, secured to a vertical reciprocating valve rod 18. It is obvious that the valve 17 is seated by a downward movement and unseated when moved upwardly.

Each of the outlet openings 8 is covered and uncovered by an upwardly seating outlet valve 19, secured to an upstanding reciprocating valve rod 21, as shown. It might be stated at this point, that when the valve 17 is open, the valve 19 is closed and vice versa.

Each of the drinking receptacles 5 has its upper open end closed or covered by a vertically swinging lid 22, serving to prevent leaves, dirt or the like from entering the same. As more clearly shown in Fig. 2, the vertically swinging lid is provided near its inner end with upstanding apertured ears or knuckles 23, receiving bolts 24, passed through apertured ears or knuckles 25, rigidly secured to the drinking receptacle and preferably formed integral therewith, as shown. At its outer end the lid 22 extends beyond the corresponding end of the drinking receptacle for a substantial distance and is preferably bent upwardly slightly for providing a lip 26, whereby the animal may readily raise the lid to the open position, when desirous of drinking the water. The lid is provided at its inner end and centrally thereof with an opening 26', whereby the lid may be swung upwardly without engaging the T-coupling 11. Adjacent the

inner end of the opening 26' are spaced depending apertured ears or knuckles 27, receiving a pivot pin 28, passed through an eye 29 formed upon the lower end of the 5 valve rod 18. As more clearly shown in Fig. 2, the lid 22 carries near its inner end, pairs of depending apertured ears or knuckles 30, receiving a pivot pin 31, passed through an eye 32 formed upon the upper 10 end of the valve rod 21. Each lid has two pairs of knuckles whereby the lids are interchangeable.

From the foregoing description, it is obvious that when the lid 22 is elevated the 15 inlet valve 17 is unseated while the outlet valve 29 is seated, thus supplying the water to the drinking receptacle, and retaining the same therein. The lid is raised by the animal, which after drinking, allows the same 20 to descend, whereby valve 17 is closed and valve 19 opened, the water contained within the receptacle 5 thus being allowed to drain from the same.

It is to be understood that the form of my 25 invention herewith shown and described is to be taken as a preferred example of the same, and that certain changes in the shape, size and arrangement of parts may be resorted to without departing from the spirit 30 of the invention or the scope of the subjoined claims.

Having thus described my invention, I claim:

1. A sanitary stock watering apparatus, 35 comprising a drinking receptacle, a normally open outlet valve for the receptacle whereby the receptacle is normally empty, a water supply conduit discharging into the receptacle and having its discharge end 40 spaced from and out of engagement with all walls of the receptacle and vertically spaced a substantial distance from the maximum water level of the receptacle, a normally closed valve for the water supply conduit to control the passage of water therethrough, and a cover pivotally connected with the receptacle and adapted when closed to exclude foreign matter from the receptacle and having operative connection with 45 the inlet and outlet valves to close one and open the other.

2. A sanitary stock watering apparatus, comprising a drinking receptacle having an overflow outlet for determining the maximum water level of the receptacle, a normally open water outlet means for the receptacle whereby the receptacle is normally empty, a water supply conduit for discharging water into the receptacle and having its 55 discharge end spaced a substantial vertical distance from the maximum water level of the receptacle and spaced from and out of contact with all walls of the receptacle, a normally closed valve arranged within the 60 water supply conduit, a swinging cover ar-

ranged adjacent the top of the receptacle and adapted when closed to prevent foreign matter from entering the receptacle, and means operated upon the movement of the cover to the open position for opening the 70 inlet valve and closing the outlet means.

3. A sanitary stock watering apparatus, comprising a plurality of drinking receptacles, a common water supply conduit for the receptacles, an individual water supply conduit connected with the common water supply conduit and discharging into each drinking receptacle and having its discharge end arranged in a higher plane than the maximum water level of the receptacle, an inlet 75 valve associated with the individual water supply conduit and normally closed to prevent the passage of the water therethrough, a normally open outlet valve for each receptacle whereby the receptacle is normally 80 empty, and a movable cover to exclude foreign matter from the receptacle and connected with the inlet and outlet valves to 85 open one and close the other.

4. A sanitary stock watering apparatus, comprising a drinking receptacle, a normally open outlet valve for the drinking receptacle whereby it is normally empty, a substantially vertically swinging cover disposed adjacent the top of the receptacle and adapted when closed to exclude foreign matter from the receptacle and having an opening arranged near its pivot, a water supply conduit arranged above the receptacle and having its discharge end adapted to 90 enter the opening of the cover when it is swung upwardly, a normally closed valve arranged within the water supply conduit, and means operated upon the movement of the cover in one direction to open one valve 95 and close the other.

5. A sanitary stock watering apparatus, comprising a shell having a transverse partition dividing the same into a pair of separate drinking receptacles and provided with an opening, an overflow conduit arranged within the opening of the partition with its upper end in communication with the upper portions of both receptacles for controlling the maximum water level thereof, a substantially vertically swinging cover for each receptacle and adapted when closed to exclude foreign matter from the receptacle, a water supply conduit for each receptacle having its discharge end arranged above the 100 cover of the receptacle, an inlet valve associated with each water supply conduit and normally closed, a normally open outlet valve for each receptacle whereby the receptacle is normally empty, and means operated upon the movement of the cover in one direction to open one valve and close the other.

6. In a sanitary stock watering apparatus, a drinking receptacle having its top open, a 105

cover pivotally connected with the receptacle to normally close its open top and provided near its pivot with a water inlet opening, a normally closed water supply valve 5 structure embodying an inlet valve arranged above and spaced a substantial vertical distance from the cover and disposed to supply the water to the water inlet opening of the cover, a normally open outlet valve arranged 10 near the bottom of the receptacle, a member connected with the cover and depending therefrom and connected with the outlet valve, and a member connected with the cover and extending upwardly therebeyond 15 and connected with the inlet valve.

7. In a sanitary stock watering apparatus, a drinking receptacle having its top open, a vertically swinging cover pivotally connected with one end of the receptacle and 20 provided with a water inlet passage, a water supply conduit arranged above the cover and spaced a substantial vertical distance therefrom and adapted to supply the water into the receptacle through the passage of 25 the cover, a normally closed inlet valve associated with the supply conduit, a normally open outlet valve arranged near the bottom of the receptacle whereby the receptacle is normally empty, a rod arranged 30 above the cover and pivotally connecting the inlet valve and cover, and a rod arranged below the cover and pivotally connecting the outlet valve of the cover.

8. A sanitary stock watering apparatus, 35 comprising a plurality of drinking recep-

tacles, water supply means for the receptacles, an inlet valve structure embodying an inlet valve for each receptacle, connected with the water supply means and vertically spaced a substantial distance from the maximum water level of the receptacle so that the water in the receptacle cannot flow back into the water supply means, an outlet valve for each receptacle, and a cover pivotally connected with each receptacle and having operative connection with the inlet and outlet valves to open one and close the other. 40

9. A sanitary stock watering apparatus, comprising a drinking receptacle, a normally open outlet valve for the receptacle 50 whereby it is normally empty, a water supply conduit adapted to discharge into the receptacle and having its discharge end disposed in a higher plane than the maximum water level of the receptacle, an inlet valve 55 associated with the water supply conduit and normally closed to prevent the passage of water through the conduit, and a movable cover for the receptacle and adapted when in the closed position to exclude foreign 60 matter therefrom and having operative connections with the inlet and outlet valves to open one and close the other.

In testimony whereof I affix my signature in presence of two witnesses.

JOHN M. B. LEWIS.
